PUSH-PULL AMPLIFIER

Raymond O. Wise, Orange, N. J., assignor to Bell Telephone Laboratories, Incorporated, New York, N. Y., a corporation of New York

Application June 13, 1934, Serial No. 730,387

6 Claims. (Cl. 179—171)

This invention relates to push-pull vacuum tube circuits and more particularly to means for automatically balancing said circuits.

The main object of the invention is to maintain an automatic balance between the direct currents in the anode circuits of a pair of vacuum tubes.

In accordance with the invention, the equalization of the space currents of a pair of vacuum tubes connected in push-pull is carried out under the control of a differential voltage that is set up whenever the space currents are unbalanced. The differential voltage is introduced in the input circuit of the tubes in serial relation to the two grids, causing one grid to be made more positive and the other more negative with respect to the cathodes. It is so arranged that the application of these grid voltages causes the larger space current to decrease and the smaller to increase until an equilibrium is set up in which the space currents are substantially equal again, although both may have departed from their initial value.

The invention is applicable to amplifiers whose filament current supply is either direct current or alternating current provided the following conditions are observed: (1) If direct current is used, separate batteries should be employed for the two filaments; (2) if directly heated filament type cathode tubes are to be operated on alternating current through a power transformer, separate filament current windings should be provided for the two tubes; (3) if indirectly heated cathode tubes are employed both heaters may be connected to a common source of either direct or alternating current.

The objects and advantages of the invention will be better understood from the following detailed description thereof when read in connection with the accompanying drawing in which, Fig. 1 shows a push-pull electronic vacuum tube amplifier employing directly heated filament type cathodes operated on separate batteries and equipped with automatic plate current balance circuits in accordance with the invention.

Fig. 2 shows the circuit of Fig. 1 modified to employ separate windings on an alternating current power transformer to heat the vacuum tube cathodes, and,

Fig. 3 shows the circuit of Fig. 1 modified to employ vacuum tubes having indirectly heated cathodes operated either from a common battery or from the same winding of a power transformer.

The circuit of Fig. 1 comprises a source of alternating current 1, an input transformer 2 hav-

ing a center tapped secondary winding for applying energy symmetrically to the grids of the vacuum tube amplifiers 3 and 4, and an output transformer 5 for coupling the plate circuits of the vacuum tubes to a load resistance 6. Plate voltage is supplied to the vacuum tubes 3 and 4 by a battery 7 through the center tapped primary winding of the output transformer 5, and a fixed portion of the grid bias is furnished by a battery 8 through the center tapped secondary winding of the input transformer 2. The automatically variable portion of the grid bias on the vacuum tubes 3 and 4 is supplied by the plate current flowing through the resistances 9, 10, 11 and 12. Condensers 13 and 14 whose impedances at signal frequencies are small compared with those of the resistances 9, 10, 11 and 12, serve to prevent degenerative action on waves passing through the amplifier. Separate batteries, 15 and 16, are employed to heat the filaments of the vacuum tubes 3 and 4.

The operation of the circuit is as follows: It will first be assumed that the bias on the grids of the vacuum tubes 3 and 4 due to the battery 8 is such as to permit appreciable plate current from the battery 7 to flow through the split primary winding of the output transformer 5, the plate to cathode impedances of the tubes, and the resistances 9, 10, 11 and 12. It will be further assumed that the grid bias versus plate current characteristics of the vacuum tubes 3 and 4 are somewhat different so that when identical bias voltages are applied to the grids, the plate currents flowing in the two tubes are not the same.

The plate current of the vacuum tube 3 from the positive terminal of the battery 7 divides at the junction of the resistances 9 and 11, one portion flowing down through the resistances 11 and 12 and up through the resistance 10, while the other portion flows down through the resistance 9. The two portions of the plate current of the vacuum tube 3 reunite at the junction of the resistances 9 and 10 to flow to the negative terminal of the battery 7. The plate current of the vacuum tube 4 from the positive terminal of the battery 7 divides at the junction of the resistances 10 and 12, one portion flowing up through the resistances 12 and 11 and down through the resistance 9, while the other portion flows up through the resistance 10. The two portions of the plate current of the vacuum tube 4 reunite at the junction of the resistances 10 and 9 to flow to the negative terminal of the battery 7.

The portion of the bias due to the battery 8 is,

of course, the same on both grids of the vacuum tubes 3 and 4, so that on the basis of the original assumptions, the plate current of tube 3, say, will initially be greater than that of tube 4. 5 While this condition holds, the plate current from tube 3 flowing down through the resistances 11 and 12 will exceed the oppositely directed plate current of tube 4 flowing through the same resistances. The cathode of tube 3 thus becomes 10 effectively more positive with respect to its grid while at the same time the cathode of tube 4 becomes less positive. As a result of these changes in bias, the plate current of tube 3 is reduced and that of tube 4 is increased so that 15 they are more nearly equal than they would be if fixed bias voltages of equal magnitude were applied to both grids.

The circuit of Fig. 2 differs from that of Fig. 1 only in that separate windings 17 and 18 on a 20 power transformer 19 are used to supply alternating current to the directly heated filament type cathodes of the vacuum tubes 3 and 4. The operation of the circuit of Fig. 2 is otherwise identical with that of Fig. 1.

25 The circuit of Fig. 3 differs from that of Fig. 1 in that indirectly heated cathodes 20 and 21 are used instead of directly heated filament type cathodes. The heaters may have direct current supplied from a common battery 22 or alternating current from a common winding 23 of a power transformer 24. The operation of the circuit of Fig. 3 is likewise identical with that of Fig. 1.

30 By a similar method of procedure, the plate current of the two tubes can be shown to approach equality automatically when that of tube 4 initially exceeds that of tube 3.

The invention is not limited to systems employing three electrode tubes but may be used 35 with tubes having any desired number of electrodes. In multi-electrode tubes the space current may include components from the several grids as well as from the anode.

What is claimed is:

40 1. In an electrical circuit, vacuum tubes arranged in push-pull relation, each tube including a grid, a cathode, and an anode, means to set up a voltage determined in magnitude and polarity by the difference between the space currents of the tubes, and means to impress portions of said voltage in opposite polarity upon the grids of the tubes to substantially equalize the space currents.

45 2. In an electric circuit, vacuum tubes arranged in push-pull relation, each tube including a grid, a cathode, and an anode, means to insure the same space current flow in each tube, comprising electrical means for controlling the

grid potential of each tube, said means being actuated by a difference in the space current flow in the tubes.

5 3. In an electric circuit, vacuum tubes arranged in push-pull relation, each tube including a grid, a cathode, and an anode, means to insure equal anode direct current flow in the tubes, comprising a separate resistance element in each anode circuit, and means controlled by the difference in the IR drops through the resistances due to the anode currents, said means controlling the grid potentials of the respective tubes.

10 4. In combination with a pair of vacuum tubes in push-pull connection, impedances individual to the space current paths of the tubes and having a terminal in common, a divided impedance bridged between the non-common terminals of the individual impedances, a conductive connection from the grid of each tube to the division point of the divided impedance, and a conductive connection from the cathode of each tube to the non-common terminal of the impedance individual to such tube, whereby the potential of each grid with respect to its corresponding cathode is 15 made to depend upon the difference in the space currents in the respective tubes.

20 5. In combination with a pair of vacuum tubes in push-pull connection, a pair of substantially equal resistances each individual to the space current path of one tube and having a terminal in common, a resistance bridged between the non-common terminals of the individual resistances, a conductive connection from the grid of each tube to the mid-point of the bridging resistance, and a conductive connection from each cathode to the non-common terminal of the associated individual resistance, whereby the space currents of the respective tubes are automatically maintained substantially equal.

25 6. In combination with a pair of vacuum tubes in push-pull relation, a pair of substantially equal resistances having a terminal in common and each resistance being individual to the space current path of one tube, a resistance bridged 30 between the non-common terminals of the individual resistances, a conductive connection from the grid of each tube to the mid-point of the bridging resistance, and a conductive connection from each cathode to the non-common terminal of the associated individual resistance, whereby an inequality of space currents in the tubes causes a positive increment of potential 35 to be impressed upon the grid of the tube having the smaller space current and a negative increment upon the grid of the tube having the larger space current.
